METHOD OF AND MEANS FOR ATTACHING
HEELS TO SHOES

Harold B. Wood, Jennings, Mo.

Application January 12, 1937, Serial No. 120,196

2 Claims. (Cl. 145—128)

My invention relates to the attachment of heels to shoes.

In attaching heels to shoes, it has been the practice to apply a temporary fastening device to a lasted shoe and its heel to draw the heel against the heel seat portion of the shoe, and then later remove the temporary fastening device and replace it with a permanent fastening device such, for instance, as a screw.

10 In my improved method of attaching heels, it is an object of my invention to employ but one fastening device, a wood screw, and its application to the shoe and heel therefor is permanent, thus eliminating the usual temporary fastening step, and, to this end, I employ the usual last having a heel section provided with a thimble hole for jacking the last, and I provide the heel section of the last with an inclined bore extending from the upper face of the heel section to the lower face of the heel section. I also provide the lower, or heel seat face of the last with a metal plate having a hole of less diameter than the inclined bore in the heel section, and, which hole is in axial alignment with the bore to provide a shoulder in a plane with the lower face of the heel section of the last to serve as a stop for a tool guide, which guide can be used separately from the tool, or as a part attached thereto, and, by tool I mean a tool to drill a hole through the heel seat portion of a lasted shoe and into a heel to be attached thereto, and, to simultaneously countersink the upper end of the hole, and a tool to force a screw into the hole and move it into home position for permanently securing the heel to the shoe.

35 The manner in which the above and other objects of the invention are secured, and the means employed, will be apparent from the following description, and the accompanying drawing, in which:

40 Fig. 1 is a fragmentary sectional view showing the heel portion of shoe last with a part of a shoe mounted thereon, and the last being provided with devices for protecting an opening in the heel portion of the last and a tool to drill a hole in a heel, to be secured to the shoe by means of a screw, as well as countersinking the material of the heel seat portion of the shoe.

45 Fig. 2 is a view similar to Fig. 1, but showing device for protecting the opening in the last as unsecured to the drilling and countersinking device.

50 Fig. 3 is a view similar to Fig. 2, showing a device within the opening protecting device for securing a screw to the heel of a shoe.

Fig. 4 is a fragmentary sectional view of the heel portion of a shoe last and a metal plate secured thereto having an opening of less diameter than the opening in the heel portion of the shoe last to provide a stop shoulder for the opening protecting device.

5 Fig. 5 is a view partly in sectional elevation and partly in side elevation of the tube or device for protecting the opening in the heel portion of the shoe last, said tube being removable from the 10 opening.

Referring to the drawing, the reference numeral 1 designates the heel portion of a shoe last which may be of the usual type provided with a thimble hole 2 for jacking the last, except for such other 15 constructional features and associated parts as hereinafter fully described as pertaining to my present invention.

In carrying out my invention, I provide the heel section 1 of the last with a bore 3 between the 20 thimble hole 2 and the rear face 4 of the heel portion of the last. The bore 3 extends from the top face of the last to and through the lower face of the last, and the bore is disposed at an angle to the axis of the thimble hole 2, or, in other 25 words, it converges at its lower end toward the axis of the thimble hole 2.

I provide the lower face of the heel section of the last with a metallic nail clinching plate 5, which is suitably secured thereto, and the plate 20 5 is provided with an opening 6 in axial alignment with the axis of the bore 3. The plate opening 6 is of less diameter than the bore 3 and the plate at the edge portion of the opening 6 therein serves to provide a stop shoulder 7 for 35 a removable tubular metal lining, or sleeve 8 for the bore 3.

The tubular lining or sleeve 8, in one embodiment of the invention is associated with a tool embodying a shank 9 having a longitudinal bore 40 10 therethrough. The lower face of the shank 9 is formed to provide a bevel, or countersink cutter 11. The upper end of the shank bore 10 is screw threaded to receive an adjusting screw 12. A steel shaft 13 is disposed within the bore 10 45 below the adjusting screw 12, and the shank 14, of a suitable drill 15, is receivable in the lower end of the bore with the drill 15 projecting beyond the countersink cutter 11. The drill shank 14 is held against rotation relative to the tool shank 9 by means of a set screw 16, and it is held against upward movement into the shank bore by the steel shaft 13 and the adjusting screw 12.

A suitable stop collar 17 is mounted on the tool shank 9, and the collar is provided with a hole 55

18 on one face thereof, which is adapted to receive the upper end of the tubular member 8. The tubular member 8 is provided with an opening 19 through which a set screw 20, carried by 5 the collar 17 passes for end contact with the tool shank 9. The screw 20 holds the collar 17 in its adjusted position on the tool shank 9. When the drilling and countersinking tool is thus provided with the tubular member 8, it can be 10 inserted, as a unit into the bore 3 of the shoe last and the lower end of the tubular member stops and rests against the metal plate shoulder 7 at the edge of the plate opening 6. When in this 15 position in the bore 3 of the last, it will be observed, that the tubular member 8 resting on the shoulder 7 prevents the hole in the heel being drilled too deep, likewise the countersink in the heel portion of the lasted shoe. Further, the 20 tubular member 8 serves to protect the bore against injury or wear as the tool is rotated in the bore 3.

It will be apparent that when the collar 17 is 25 reversed on the shank 9, that the tubular member does not rotate with the shank 9 and thus does not rotate in the bore 3, but merely serves as a removable liner therefor.

It will be apparent from the drawing that the 30 collar 17, as well as the tubular member 8 are removable from the tool shank carrying the drill and countersink cutter and can be attached to a screw driver shank 21. When used with a screw driver, it is apparent that it is for the purpose of forcing a fastening screw through the heel portion of the shoe and into the drilled opening in 35 the heel for permanently attaching the heel to the shoe.

The many advantages of the herein described 40 invention will readily suggest themselves to those skilled in the art to which it appertains.

From the foregoing description, it is evident 45 that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing

from the spirit of the invention within the scope of the appended claims.

What I claim is:

1. A tool for use with a shoe last having a bore therethrough and a plate having a hole of less diameter than the bore to provide a metal shoulder, said tool comprising a shank having a longitudinal bore therethrough, a drill insertable into the bore from the lower end thereof, the upper end of the bore being screw threaded, a 10 screw threaded into the screw threaded bore and serving as a stop for the upper end of the drill, a set screw carried by the shank for preventing rotation of the drill relative to the shank, a countersink cutter formed on the lower end of the 15 shank, a sleeve mounted on the shank, a gauge collar having a bore to receive the shank and having a bore of larger diameter to receive the upper end of the sleeve, and a set screw insertable through a screw threaded opening in the 20 collar and an opening in the sleeve for vertically adjustably securing the sleeve to the shank to prevent rotation of the sleeve relative to the shank and to cause the lower face of the sleeve to serve as an annular shoulder adjacent the 25 countersink cutter to engage said metal shoulder on the last, and said collar being reversible on the shank to serve as a stop to act against the upper end of the sleeve when the sleeve is used as a guide for the shank to pass through and to 30 turn in when the sleeve is used as a removable lining for the last bore so that the shank can turn relative thereto instead of therewith.

2. A tool of the class described having, in combination, a shank having a longitudinal bore 35 therethrough, a counter-sink cutter formed on the lower end of the shank, a drill insertable into the shank bore, means for adjustably securing the drill in position, means adjustably carried in the bore of the shank serving as a stop for the inner end of the drill, a sleeve mounted on the shank, a reversible collar adjustably secured to the shank to serve as a stop to limit downward movement of the shank relative to the sleeve, and means for connecting the sleeve and the 40 collar to rotate as a unit when desired.

HAROLD B. WOOD.
